HAIR CURLER

Nathan L. Solomon, Brooklyn, N. Y.

Application January 25, 1935, Serial No. 3,402

3 Claims. (Cl. 132—41)

The present invention has to do with means for treating hair and particularly is concerned with a hair curler comprising complementary clamping members about which the hair is spirally wound longitudinally thereof and subsequently held in such relation by a swingable resilient loop carried by one of the complementary members. Hitherto in the manufacture of hair curlers of the character referred to it has been customary to permanently secure the complementary clamping components or members together. This operation increased the cost of manufacture. Apart from permanently securing the complements, the swingable resilient loop usually associated with the complements was likewise permanently but swingably secured to one of the complements. Such a construction, from the standpoint of manufacture also increased the cost of production. Accordingly, the object of the invention is to provide a simplified hair curler of the type referred to in which the clamping complements are disconnectably associated and in which the resilient or elastic loop which coacts to sustain the coiled hair about the complements in place is removably connected to one of the complements. The invention has as an important object to provide a simplified hair curler of the character alluded to which comprises few constituent parts, and which may be readily and quickly assembled without the aid of special rivet fastening machines or the like. The invention comprehends as a further object the provision of a hair curling device comprising a perforated tube adapted to removably sustain an arcuate cover, the tube and cover forming the complementary clamping components above referred to, the cover having inwardly disposed nipples or annular projections rotatably associated with one end of the tube and constituting means for removably guiding and supporting the free terminals of a resilient loop forming holding means to sustain, as previously pointed out, the hair wound about the complements in a desired relation.

The invention further comprehends as an object to provide a hair curler having complementary clamping components in the form of a tube and arcuate cover, the latter having inwardly arranged and diametrically disposed tapering hollow nipples which may be manually pressed over one end of the tube to permit the opposed nipples to spring into aligned openings at one end of the tube to provide a pivotal connection to

permit the cover to be swung relative to the companion tube.

The invention further contemplates as an object to provide a cover having inwardly overhanging nipples or projections cooperating with one end of a tube to provide a disconnectible pivotal connection.

The invention has as a further object to provide complementary clamping members having a pivotal connection comprising opposed nipples or annular instrumentalities to removably and rotatably guide opposed free terminals of a resilient loop appropriately carrying at a one end thereof a spheroidal element adapted to disconnectibly interlock with one end of one of the complementary members.

The invention further comprehends as an object the provision of complementary clamping members constituting a tube and cover, the cover having overhanging and opposed hollow nipples disconnectibly associated with one end of the tube which includes means for disconnectibly holding one end of a flexible and pliable elastic cord constituting a closed loop on which is slidably mounted a stay having a restricted or reduced portion adapted to be removably and telescopically associated with another end of the tube whereby the sides of the loop may be distended to hold the hair wound about the complements in place.

Other objects, advantages and features of the invention are in part obvious and in part pointed out hereinafter and the invention will be best understood and appreciated from the following description of several preferred embodiments thereof selected for purposes of illustration and shown in the accompanying drawing in which:

Fig. 1 is a longitudinal sectional view of one form of hair curler according to my invention.

Fig. 2 is a sectional view taken on the line 2—2 of Fig. 1 but on a larger scale.

Fig. 3 is a longitudinal plan view of the form illustrated in Fig. 1.

Fig. 4 illustrates in perspective an exploded view of the curler shown in Figs. 1—3 inclusive.

Fig. 5 shows end views of the complementary clamping members constituting a tube and arcuate cover, and as illustrated the cover is in position above the tube prior to pressing the former over the tube to be pivotally carried by the latter.

Fig. 6 illustrates in perspective the several unassembled parts of a modified hair curler according to the invention.

Fig. 7 is a longitudinal and sectional view of

a hair curler of the type disclosed illustratively in Fig. 6.

Fig. 8 is a fragmentary view of an elastic loop on which a stay is mounted and

5 Fig. 9 is a perspective view of the stay carried by the form shown in Figs. 6-8 inclusive.

In all of the forms illustrated, the hair curler according to the invention comprises complementary clamping members 10 and 11. Complementary member 10 is a perforated tapering tube. 10 Complementary member 11 takes the form of an arcuate and perforated cover having tapering sides as 12 adapted to embrace correspondingly shaped adjacent faces of tube 10 and in all of 15 the forms disclosed cover 11 is provided with integrally depending rearwardly disposed spaced lugs or ears 13 each of which includes an inwardly arranged overhanging tapering projection in the form of a nipple or hollow annulus 20 as 15 integral with a respective lug 13.

As shown in Fig. 3, tube 10 includes diametrically opposed relatively large tapering openings 16 which serve to receive the spaced tapering nipples 15 which are rotatable relative to the 25 tube to form a pivotal or hinged connection whereby the cover may be swung relative to the tube and to increase the resiliency of the latter adjacent openings 16 thereof, the body of the tube (see Fig. 4) is provided with spaced longitudinally disposed and diametrically opposed striations or slots 17. The complementary clamping members may be made of any suitable stock, such as of any suitable relatively light weight sheet metal, for example, aluminum or 30 the like, but if desired, the invention comprehends the utilization of other stock, namely a suitable hard rubber or wood.

40 Swingably associated with cover 11 of the form illustrated in Figs. 1 to 4 inclusive is a loop 18, formed from resilient wire and comprises rectilinear legs 19 and 20 integral with a common intermediate portion 21' and having inwardly bent free terminals 21 and 22 disposed in superimposed relation.

45 Prior to attaching loop 18 to the cover 10, a spheroidal perforated stay 23 is slidably passed over one terminal and side of the loop and shifted to be sustained on and by the intermediate portion 21'. As illustrated in Figs. 1, 2 and 4 the 50 stay is of rubber, but obviously, the spheroidal stay may be of wood or any other appropriate material.

55 In assembling the curler according to Figs. 1 to 4 inclusive, the cover is first placed on the tube so that the spaced lugs or ears 13 straddle the latter and the spaced nipples abut the upper portion 24 of the tube. Subsequently finger pressure is applied to the rear end or bridge 25 of the cover whereby the nipples ride downwardly relative to the tube, causing spaced ears 13 to spread after which the nipples register with their associated tapering openings 16. The nipples now move inwardly being guided by the walls of opening 16, that is, in a direction towards each 65 other due to the release of the energy stored up in the resilient lugs after having been pressed outwardly.

70 With the nipples disposed in their respective openings of the tube, a pivotal or hinged connection is formed, whereby the cover may be swayed relative to the tube. Having pivotally attached the cover, the loop is then pivotally or hingedly connected to the cover. More specifically each of the terminals 21 and 22 is passed 75 or threaded through a guide bore 28 of a respec-

tive nipple whereby the terminals of the loop are disposed within the tube and in such relation that they are angularly offset in respect to the horizontal axis of the tube, but in overlapped relationship. Consequently the spring tension of 5 the terminals due to their offset position within the tube causes adjacent faces of the terminals to frictionally engage. Arranged in this fashion, the loop is held substantially closed and may be manually swung relative to the cover and tube. 10 Although terminals 21 and 22 are rotatably sustained by the spaced hollow nipples, they may be 15 slidably displaced laterally and outwardly in proportion to the amount of hair wound about the complements, such lateral movement taking place during rotating of the loop for interlocking the stay of the latter with the tube. Hence arms 19 and 20 of the loop are automatically 20 displaceable to adjust themselves relative to the clamping components depending upon the thickness of the amount of hair treated.

As illustrated in Figs. 1 and 3, cover 11 is closed and stay 23 of the loop is removably interlocked at one end of the tube. If finger pressure be applied to stay 23, the latter may be displaced from 25 the tube and the loop may be swung rearwardly such that terminals 21 and 22 rotate relative to associated nipples 15. Cover 11 may then be raised or swung rearwardly. In such relation, nipples 15 rotate relative to the body of the tube. 30 In such position, the cover may be defined as "opened".

40 In use, the cover is first opened after which a portion of the hair to be treated is placed between the cover and tube. Pursuant thereto the cover is closed and the remainder of the portion of hair to be treated is spirally wound about the cover and tube longitudinally thereof. The loop 18 is then closed, namely, the stay thereof is swung towards a remote opposite end of the tube whereby the sides of the loop hold the hair wound about the complements in place after the stay thereof has been snapped into interlocking engagement with the tube as is well appreciated and understood.

45 In the form according to Figs. 1 to 4 inclusive, the loop may be conveniently removed from the cover by spreading legs 19 and 20 outwardly permitting the terminals 21 and 22 thereof to be free of the nipples and the cover may be readily detached from the tube by spreading the spaced lugs 13 outwardly to diverge the latter until the nipples 15 are clear of openings 16 of the tube. It follows therefore that if one of the parts of the curler, above alluded to, becomes defective, a 50 new similar part may be conveniently and quickly substituted and by an inexperienced person without the use of any tools whatsoever.

55 In accordance with the form illustrated in Figs. 6, 7, and 8, loop 18 is in the form of an elastic cord. This loop has its ends 29 and 30 appropriately secured by a clasp 31, thus forming a closed loop which carries stay 32 comprising a relatively large head 33 having a diametrically disposed slot or striation 34 which communicates 65 with a relatively large diametrically disposed channel 35.

60 The width of the elastic cord of the loop is slightly greater than the width of slot 34 and in order to pass the cord through slot 34, the cord 70 is first slightly stretched and passed downwardly through slot 34 until the cord reaches channel 35 after which tension on the cord is released. Accordingly the width of the cord increases to a 75 width greater than the gap constituting slot 34.

It follows therefore that the loop may be quickly attached to the head of the stay and although the stay may be shifted relative to the loop, the latter will not disconnect from the head unless the cord is again manually distended or stretched after which it may be passed outwardly through the narrow slot 34.

The perforated tube 10, shown in Figs. 6 and 7 includes means for disconnectibly holding the attached terminals 29 and 30 of the loop. For this purpose, diametrical disposed portions of tube 10 is provided with relatively narrow longitudinal disposed slots 36 each of which is in communication with an associated relatively large opening 37. To attach terminals or ends 29 and 30 to the tube, these ends are first slightly stretched and passed through the aligned slots 36 until they reach the large aligned openings 37 after which manual pressure on these terminals is removed. Consequently the thickness or width of the terminals increases and since these widths are greater than the width of the slots 36, the loop once attached to the tube cannot be accidentally removed. If, however, the loop is attached to the tube, the loop may be removed therefrom by first stretching terminals 29 and 30 and passing the stretched parts outwardly as to be free of the tube as is well understood.

Stay 33 is provided with a reduced cylindrical shank 38 which is removably received within or telescopically associated or disconnectibly interlocked with the restricted end of the tapered tube 10 and the annular shoulder 39 serves as a stop to limit the insertion of shank 38 within the bore of the tube.

In assembling the form shown in Figs. 6 and 7, cover 11 is superimposed on the tube and the rear bridge portion thereof is pressed downwardly, spreading ears or lugs 13 until the hollow nipples 15 enter the aligned openings 16 of the tube. The resiliency of the lugs 13 forces the nipples towards each other after entering aligned openings 16.

The cord of the loop is then passed through the restricted slot 34 of the head of the stay and into the large opening 35. The terminals 29 and 30 are also passed into aligned slots 36 and into the aligned openings 37 of the tube, which pivotally sustain the loop.

In use, a portion of hair is first placed between the cover and tube and the former is closed. Pursuant thereto, the hair is wound about the complements after which the stay is grasped to distend the loop so that the sides of the latter snugly hold the hair wound about the

complements in place. The shank 38 is then inserted or telescoped with the narrow end of the tube.

It is apparent that hair curlers of the character above described may be conveniently manipulated, each including few parts which are susceptible to inexpensive manufacture and ease of assembling and which without injury thereto may be readily dismantled and easily reassembled.

In the broader aspects of the invention, I do not desire to be understood as limiting its embodiments to details herein shown illustratively as a wide variety of modifications may be made within the scope of the appended claims without departing from the spirit of the invention.

I claim:

1. In a hair curler, the combination of, a tube, a clamping member having spaced hollow nipples rotatably sustained by said tube, a stay having means adapted to be removably interlocked with one end of said tube, said stay comprising a relatively narrow slot and including a relatively large channel in communication with said slot and a resilient loop adapted to be distended to permit passage of a portion thereof through said slot and retained by the latter in said channel, said tube having means for removably and swingably retaining another portion of said loop.

2. In a hair curler, the combination of, a tube, a clamping member having spaced hollow projections rotatably sustained by said tube, a stay having means adapted to be removably interlocked with one end of said tube, an elastic loop connected to said stay, said tube having aligned relatively narrow slots and relatively large openings in communication with said slots, said loop adapted to be distended to permit passage of a portion thereof through said slots and swingably retained by the walls of the latter in said openings.

3. In a hair curler, the combination of, a perforated tapering tube, a perforated clamping member having spaced nipples removably and rotatably sustained by said tube, a stay having means adapted to be removably interlocked with one end of said tube, a closed elastic loop disconnectibly associated with said stay, said tube having aligned relatively narrow slots at one end thereof and relatively large openings in communication with said slots, said loop adapted to be distended to permit a passage of a portion thereof through said slots and swingably retained by the walls of the latter in said openings.

NATHAN L. SOLOMON. 55
